UNITED STATES PATENT OFFICE.

EDWARD R. PERRIN, OF WAUZEKA, WISCONSIN.

HAMMOCK-CHAIR FOR HANDLING INVALIDS.

1,280,108.

Specification of Letters Patent. Patented Sept. 24, 1918.

Application filed May 17, 1916. Serial No. 98,160.

To all whom it may concern:

Be it known that I, EDWARD R. PERRIN, a citizen of the United States, residing at Wauzeka, in the county of Crawford and 5 State of Wisconsin, have invented certain new and useful Improvements in Hammock-Chairs for Handling Invalids, of which the following is a specification.

An object of my invention is to provide 10 a hammock chair by which invalids may be handled and moved without exerting pressure upon any part of the body or limbs, and which chair is so arranged that the invalid may be taken up from the bed and 15 moved to any desired point without being lifted by hand.

A further object is to so construct the 20 chair in which the invalid is taken that the same may be built around a person as that person is seated on the edge of a bed and the chair structure thus formed may then be suspended and raised to the proper relation to move the person from the bed after 25 which the chair structure may be again lowered to its normal position, the same operation being pursued in placing the person back in the bed.

With other objects in view, my invention 30 consists in certain novel features of construction and combinations of parts which will be hereinafter set forth more fully in connection with the drawings and then pointed out in the claims.

In the drawings:

35 Figure 1 is a view in side elevation of the device of my invention.

Fig. 2 is a top plan view of the structure disclosed in Fig. 1.

Fig. 3 is a vertical sectional view to better 40 illustrate the arrangement of the parts.

Fig. 4 is a detail view of the top of the back structure.

The support or base 1 is mounted on the 45 casters or wheels 2 which are swiveled on the under side thereof and in this way the support is carried to be capable of traveling movement. The upright frame members 3 and 4 are mounted on the sides of the base structure 1 at points approximately 50 centrally of the longitudinal extent of the member 1, and are provided with bearing notches 5 on the upper ends thereof, and a brace member 6 is received between the studs 7 carried by the uprights and is wedged 55 against the block 8 carried by the forward end of the base structure 1, suitable hooks

9 or other suitable fastening means being provided to hold this supporting brace 6 in its proper relation. The chair structure proper comprises the upright or leg members 10 which are connected together at their lower ends by the cross bar 11, the side seat members 12 being disposed at substantially right angles to the extent of the leg members 10 and the back members 13 60 then extend upwardly from the outer end of the seat members 12. It is preferable that a block 14 be mounted between the upright members 3 and 4 and that a block 15 be mounted rearwardly thereof in a spaced 65 relation so that a socket is provided in which the lower ends of the leg members 10 are received when the device is being used and thus these members will be held against accidental displacement and will at the same 70 time hold the chair structure against swinging or shifting movement. A cross bar 16 is provided to be mounted between the leg members 10, a cross bar 17 to be received between the side seat members 12 near the forward end thereof, a cross bar 18 to be mounted between the rear ends of the side seat members 12, and the cross bar 19 to be 75 mounted between the upper ends of the back members 13. A canvas or other fabric strip 80 20 has a wide hem or loop 21 formed on the lower end thereof to receive the cross bar 16, the canvas strip being then passed up over the cross bar 17, under the cross bar 18, and then upwardly and over the cross bar 19, 85 and the upper end being drawn down to hold the main extent of the fabric in such relation that a seat and back portion are provided in the chair frame. This drawing down and stretching of the fabric strip may 90 be accomplished by the use of a cord or rope 22 which has a central portion passed through rings or eyes 23 which are secured on the edge of the fabric strip, the rope 22 being then passed through the staples or 95 loops 24 carried by the side members 13, and then down to a position adjacent the leg members 10 where hooks 25 are secured to the rope to be received through the staples 26 which are mounted on the sides of the 100 leg members 10. The rope 22 also prevents the rear of the seat from spreading and thus causing the rod 18 to escape from its sockets. By shortening the extent of the rope 22 in its connection with the hooks 25, the tension 105 of the fabric may be varied and the seat and back portions provided for the chair 110

may be drawn taut or may be given slack to better adapt the same for the particular person with whom it is to be used.

A supporting lever structure 27 is fulcrumed at 28 in the notches or bearings 5 provided on the upper ends of the uprights 3 and 4, the fulcrum being preferably provided near one end of the supporting lever structure 27. The side seat members 12 have 10 staples 29 carried thereby and similar staples 30 are mounted on the back members 13, a rope 31 being secured to the short end of the structure 27 and provided with a hook 32 to be received in the staples 30 and a hook 33 which is received in the staples 29. The 15 supporting frame structure 27 is preferably made, as is better illustrated in Fig. 2, with the side bars thereof disposed in a divergent and V-shaped arrangement, and it will be 20 understood that a rope or cord 31 is connected with each of the outer ends of these divergent side members and is led to the hooks 32 and 33, so that support is provided for the chair frame structure at each side. 25 A tongue 34 is mounted on the base member 1 and has a handle 35 provided so that the structure may be moved or drawn over a floor and will roll on the casters or wheels 2. At the forward end of the supporting 30 frame structure 27, a rope 36 is secured at its one end and at the opposite side of the rope a hook 37 is provided, this rope being made of such a length that when the chair structure has been raised to the proper elevation, the hook 37 may be engaged in a 35 staple 38 carried on the forward end of the base 1, and thus the parts will be held in the proper relation.

A strip 39 is mounted in the recess provided between the block 8 and a block 40 mounted on the base 1 and this strip extends up between the cross bars 41 of the tongues 34, thus providing a support which reinforces the mounting of this tongue, the strip 45 being then extended up between the side members of the supporting lever structure 27. A pivoted block 42 is provided to be swung down against this strip 39 to hold the same in engagement against the cross 50 member 43 with which the rope 36 has connection, and thus the supporting lever structure is given greater rigidity and will thus be held against swinging down movement when the hooks 32 and 33 are disengaged 55 from the chair structure.

In the use of the device, the fabric strip 20 is spread on and over the edges of the bed, the cross bar 17 being placed beneath the same at a point where the invalid's knees 60 will break over the fabric, the cross bar 16 being inserted through the looped portion 21. The base 1 is moved to a relation that the members 10, 12, and 13 of the chair frame are on each side of the invalid and then the 65 cross bar 16 may be fitted in the sockets pro-

vided in the side leg members 10, the cross bar 17 is fitted in its proper relation, the cross bar 18 is laid across the fabric strip and is fitted in the sockets provided in the side back members, and the cross bar 19 has 70 the upper end of the fabric laid thereacross and this cross member is then inserted in the proper relation after which the rope 22 may be led through the rings or eyelets 23 and through the staples 24 and down to 75 connect with the hooks 25 which are received in the staples 26 to hold the fabric strip stretched to the proper tension. With the parts thus fitted, the invalid is still resting on the bed and by exerting a downward pull 80 on the outer end of the supporting lever structure adjacent the mounting of the cross member 43, after raising the block 42, the chair structure will be raised by reason of the fact that the hooks 32 and 33 have been 85 inserted through the staples 30 and 29, and the handle 35 of the tongue 34 may then be grasped and the base and structure carried thereby rolled from the point of proximity to the bed, after which the downward pressure exerted upon the structure 27 may be relieved and the parts will be supported in the relation shown in Figs. 1 and 3 with the lower ends of the leg members 10 in the 90 opening provided between the blocks 14 and 15 and thus held against swinging or twisting displacement. 95

It is preferable that the blocks 44 be mounted on the upright members 3 and 4 in a relation that they will have bearing 100 against the leg members 10 from the outside to prevent displacement of the same, and in this connection it is also perhaps desirable that the stop blocks 45 be mounted on the uprights 3 and 4 in such a relation that as 105 the cross bars and the fabric have been assembled in the chair frame, the side members 12 will be received between these stop blocks 45 and the structure will thus be held against separating movement. A foot rest 110 46 is provided on the brace member 6 and if desired, this foot rest might be made to be adjustable in any desired manner.

While I have set forth only the manner in which the parts are assembled to move an invalid from the bed, it will be apparent that the return to the bed may be accomplished in the same way by removing the structure, with the supported chair raised slightly, to a position adjacent the bed edge, 115 then permitting the chair to lower so that the fabric seat thereof will be upon the edge of the bed and disassembling of the parts in the inverse order of their assembly.

In the present disclosure but a single 125 adaptation and construction of the device is illustrated, however, it will be understood that various modifications might be resorted to in the form and arrangement of the parts as well as in the manner of connecting the 130

same, and hence I do not wish to be limited to the exact disclosure, but only to such points as may be set forth in the claims.

I claim:-

6. 1. A hammock chair for handling invalids comprising a base structure, uprights mounted on said base structure, a chair structure to be built up around the person to be moved, and means mounted on the uprights to have the chair structure connected therewith in a manner that the same is rigidly supported and carried by the base structure.
10. 2. A hammock chair for handling invalids comprising a chair structure to be built up around a person to be moved and consisting of side frame members, a fabric strip, cross bars to be connected between the side frame members to mount the fabric strip, a base structure, upright standards carried by said base structure, adapted to hold the side frame members assembled, supporting means fulcrumed on the upper ends of the standards, and means connected 25 with one end of the supporting means to be connected with and support the chair structure.
30. 3. A hammock chair for handling invalids comprising a base structure, standards mounted on the base structure at spaced apart points, a supporting structure fulcrumed on the upper ends of the standards to be capable of swinging movement, a chair structure to be rigidly connected in contact 35 with the standards, and means carried by one end of the fulcrumed supporting means to be connected with the chair structure to mount the same to be carried by the base structure.
40. 4. A hammock chair for handling invalids comprising a chair structure, a mov-

able base structure, sockets provided upon the base structure for supporting the chair structure, upright standards carried by said base structure, a brace rod for supporting 45 said standards, a V-shaped supporting lever fulcrumed upon the upper end of the standards, means depending from one end of the lever for supporting the chair, and means depending from the other end for holding 50 the lever in the proper position.

5. A hammock chair for handling invalids comprising a separable chair structure, a movable base structure, upright standards secured to the base structure, stop 55 blocks secured to the standards to prevent the chair structure from separating, a V-shaped lever fulcrumed upon the upper end of the said standards and connected with the chair structure to support it, and means 60 for preventing the lever from swinging downwardly when the chair is disconnected.

6. A hammock chair for handling invalids comprising a separable chair structure, a movable base structure, upright 65 standards secured to the base structure, a brace rod for supporting the standards, stop blocks secured to the standards to prevent the chair from separating, a V-shaped lever fulcrumed upon the upper end of the standards, means depending from one end thereof, for supporting the chair, means depending from the other end for holding the lever in the proper position, and means for preventing the lever from swinging downwardly when the chair is disconnected. 70 75

In testimony whereof I affix my signature in presence of two witnesses.

EDWARD R. PERRIN.
